(57) **CLAIM**

The ornamental design for a vehicle front lower grille as
shown and described.

DESCRIPTION

FIG. 1 is a front elevational view of a vehicle front lower grille, showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a top, front and left side perspective view thereof;
and,

FIG. 7 is a bottom, front and left side perspective view
thereof.

The claimed design is indicated by the relatively dark
portions in the figures. The de-emphasized and relatively
light portions form no part of the claimed design.

1 Claim, 7 Drawing Sheets
